TROUSER LENGTH MARKING GAGE

Ragnar M. Magnusson, Berkeley, Calif.

Application August 5, 1957, Serial No. 47,216

Term of patent 14 years

(Cl. D52—1)

Fig. 1 is a front elevation of a trouser length marking gage, showing my new design;

Fig. 2 is a side elevation of Fig. 1;

Fig. 3 is a rear elevation; and

Fig. 4 is a bottom end view.

I claim:

The ornamental design for a trouser length marking gage, substantially as shown.
